US00D800591S

(12) **United States Design Patent** (10) **Patent No.:** **US D800,591 S**
(45) **Date of Patent:** **** Oct. 24, 2017**

(54) **FLOWMETER**

- (71) Applicant: **Homeserve Plc**, Walsall (GB)
- (72) Inventors: **Graham Brett**, London (GB); **Ben Mahon**, London (GB); **Richard Miles**, London (GB)
- (73) Assignee: **Homeserve Plc**, Walsall (GB)
- (**) Term: **15 Years**
- (21) Appl. No.: **29/564,630**
- (22) Filed: **May 13, 2016**

(30) **Foreign Application Priority Data**

- Mar. 31, 2016 (ES) 003050236
- (51) LOC (10) Cl. 10-04
- (52) U.S. Cl. D10/96

(58) **Field of Classification Search**

- USPC D10/96
- CPC G01F 1/68; G01F 1/684; G01F 1/6842; G01F 1/6845; G01F 1/6847; G01F 1/688; G01F 1/6882; G01F 1/6884; G01F 1/6886; G01F 1/6888; G01F 1/69; G01K 12/02; G01K 2013/024; G01K 2013/026; G01M 3/26; G01M 3/28; G01M 3/2807

See application file for complete search history.

(57) **CLAIM**

The ornamental design for a flowmeter, as shown and described.

DESCRIPTION

FIG. 1 is a front view of the flowmeter of the present design showing a front portion of the flowmeter;

FIG. 2 is a first side view of the flowmeter of the present design showing a first side portion of the flowmeter;

FIG. 3 is a second side view of the flowmeter of the present design showing a second side portion of the flowmeter;

FIG. 4 is a back view of the flowmeter of the present design showing a back portion of the flowmeter;

FIG. 5 is a top view of the flowmeter of the present design showing a top portion of the flowmeter;

FIG. 6 is a bottom view of the flowmeter of the present design showing a bottom portion of the flowmeter; and,

FIG. 7 is a perspective view of the flowmeter of the present design showing the front, top, and first side portions of the flowmeter.

The broken lines in the drawings depict unclaimed subject matter only and form no part of the claimed design.

1 Claim, 6 Drawing Sheets
